UNITED STATES PATENT OFFICE

OTTO KRELL, OF BERLIN-DAHLEM, GERMANY

ROTATABLE HANGAR FOR AIRSHIPS

Application January 21, 1928, Serial No. 248,445, and in Germany June 7, 1927.

My invention relates to rotatable hangars for airships.

The rotatable or turning hangars for airships, as constructed hitherto, are moved by driving the wheels of the trolleys or trucks upon which the hangar rests, by means of electric motors. It is, however, a great advantage for the construction of the trucks and other structures to use the wheels of the trucks as runner wheels only and to rotate or turn the hangar by special means viz. to drag, or haul it around. A number of suggestions has been made in this direction but the problem that the hangar must be capable of being turned in one or the other direction to any desired extent, if it is to fulfill its objects, has not yet found a satisfactory solution.

According to my invention the hauling, or dragging of the hangar is effected by means of one or more ring or rings fixed concentrically to the axis of rotation of the hangar and engaged by ropes, and the like. Generally as large a ring as possible will be chosen the diameter of which is about equal to the length of the hangar so that the ring runs along the extremest circumference of the rail pit, in order to keep the power for rotating the hangar as low as possible. The drive may then take place by means of ropes or cables laid around the circumference of this ring.

Fig. 1, shows, at the top in elevation and at the bottom in plan a hangar the drive of which is effected by means of an endless rope, the driving device being stationary.

Fig. 2, illustrates, at the top in elevation and at the bottom in plan, a hangar driven by an endless rope in which the driving device is mounted on the rotatable part, while the endless rope is placed around a stationary rail.

Fig. 3, shows, in plan, an automatic hydraulic rope tensioning device.

Fig. 4, is an elevation of the device shown in Fig. 3,

Fig. 5, an arrangement of the rope tensioning device located tangentially to the periphery of the rotatable hangar, and

Fig. 6, an arrangement of the rope tension-

ing device located radially to the periphery of the rotatable hangar.

In Fig. 1 is illustrated a hangar the drive of which is effected by means of a rope *s* placed around the largest circle of the circumference *u*, this rope being raised off the circular rail at two diametrically opposite places and led over the driving devices *a*, *a'*. In this example of construction the ring is rigidly joined to the hangar and turns in unison with it. 55

If such a single ring is deemed sufficient for driving the turning hangar, it should preferably be braced or stayed by light tension members *v*, *v*, so as to maintain its shape. 65 These members *v* connect the points *b'*, *b'* of the circumference of the ring with the points *b*, *b* on the hangar, the latter being so placed that the extended tension members would intersect the ends of the diameters *d*, *d'*. If the hangar is erected in countries with strong snowfalls it is not difficult to cover up the space between the hangar and the ring by planks or boards *B*, *B* supported by light trucks running on concentric rails *h*, *h'*, *h''*. On this floor may be erected sheds for storing gas bottles and spares or serving as repair shops, care being taken that these structures do not come too near the entrance opening of the hangar so as to interfere with 70 the flow of the wind along the stern of the hangar. 75

The use of endless ropes as driving means is illustrated in the Figures 3 and 4 of the drawings. An endless rope *S* is slung around the circumference of the turntable and is wound in one turn around the two pulleys *r* and *r'*. Each of the two pulleys is driven by an electric motor *m* and *m'*, preferably of equal torque and provisions are made for 80 these two pulleys to be forced apart by a regulable or adjustable force for the purpose of contracting the loop formed by the rope. 85

In Fig. 3 this is effected by hydraulic means viz. the cylinder *z* and the plunger *k*. The cylinder is mounted upon the foundation *F* and carries at its rear end a fork within which the pulley *r* is pivoted. In a similar way a second pulley *r'* is mounted upon the external end of the plunger *k*. The pulleys can thus 90 95 100

be forced apart under regulable hydraulic pressure. On account of the variation of the distance between the two rope pulleys and the necessity to make the driving forces for both pulleys equal, the drive by means of electric motors offers particular advantages, because they may be maintained at equal torques by connecting their armatures in series. Their supply may easily be effected by means of flexible cables. No liquid is wasted in operating the mechanism and the pressure may be maintained by an accumulator which can be pumped up from time to time by means of a hand-pump, because the leakage losses only have to be made good which in the case of a correctly constructed stuffing box are very low.

In order that no bending stresses should develop at the rope ends, these rope ends S' and S'' should be parallel to the axis of the piston or plunger which in the construction illustrated in Fig. 3 is attained by placing the rope end S'' tangentially to the ring R. If it is desired to be independent as regards the arrangement of the driving device, it is only necessary to take care that the ends S' and S'' of the rope are placed in a parallel position to the axis of the piston by a corresponding arrangement of a guide pulley L in Fig. 5. For operation in both directions the arrangement shown in Fig. 6 is particularly suitable on account of the symmetric disposal of the two tangents to the ring R.

If the friction of a single rope is not sufficient for turning the hangar, a number of ropes may be employed or still better an endless rope which is slung in a number of turns around the circumference of the ring R and is then passed from the last groove over a correspondingly arranged guide roller back into the first groove of the ring. When individual ropes are used they should be subjected to a preliminary stretching until repeated stretching and slackening does no longer change the permanent expansion. In consequence of the great length of the ropes and their elasticity a sufficiently automatic equalization of the tension between the individual ropes is attained. This equalization of the load is still more favourable when the rope is wound around the pulley in a number of turns. Instead of the plain pulleys in the former case, grooved pulleys T and T' are used in the latter case, around which as in the case of the plain pulleys the individual ropes or individual rope turns or rope loops must be passed in a single turn only.

Various modifications and changes may be made without departing from the spirit and scope of the invention, and I desire, therefore, that only such limitations shall be placed thereon as are imposed by the prior art.

I claim as my invention:

1. In combination with a rectangular rotatable hangar for airships, a rope sheave

fixed to the base of said hangar of a diameter substantially equal to the length of said hanger, a single endless rope laid around said sheave in a plurality of turns, two driven grooved rope drums around which said rope is passed in a single turn in each winding, and means for forcing said drums apart by a force of suitable magnitude.

2. In combination with a rectangular rotatable hangar for airships, a rope sheave fixed to the base of said hangar of a diameter substantially equal to the length of said hanger, parallel endless ropes laid around said sheave after they have been subjected to as equal a preliminary stretching as possible, two driven grooved rope drums around which each of said ropes is passed in a single turn, and means for forcing said drums apart by a force of suitable magnitude.

In testimony whereof I affix my signature.

OTTO KRELL.
